TUYÈRE BLOCKS FOR UNDERFEED STOKERS

Jan Jurjen Groenema, Hannover-Kleefeld, Germany

Application December 14, 1956, Serial No. 628,454

Claims priority, application Netherlands
December 16, 1955

3 Claims. (Cl. 110—44)

This invention relates to improvements in tuyère blocks or blowing heads which are used for the casing of side walls of underfeed stokers.

Such tuyère blocks or blowing heads are provided with suitably distributed openings or tuyères, through which the combustion air is blown into the retort or the furnace-bed in a direction transverse to the direction of the underfeed-movement.

This invention is based on the recognition that the cooling of such tuyère blocks or blowing heads does not depend on the specific surface thereof, i.e. the proportion between the outer surface of the blowing head and the surfaces surrounding its openings, but that the cooling effect of such a tuyère block or blowing head is determined by the proportion between the cooling surface and the furnace surface thereof. In other words, the proportion between the inner surface which is swept by the combustion air, and that part of the outer surface which is turned towards the retort or the furnace bed controls the extent of cooling of the tuyère blocks.

In accordance with the instant invention, it is possible to raise this fore-mentioned proportion between the cooling surface and the furnace surface, which up to now was about 2 to 1 or 2.5 to 1, by a novel design of the blowing head to a proportion of about 10 to 1 or 11 to 1. Thus, my tuyère blocks or blowing heads share the advantages of grate rods for which, as is well known, the best proportions between cooling-surface and furnace surface are between about 12 to 1 and up to about 20 to 1.

An important object of the invention is to provide a tuyère-block or blowing head which is laminated in that it consists of two or more parts with slots therebetween, the blocks being situated at right angles to the direction of the underfeed and parallel to each other. The slots are enlarged to form relatively small openings which latter are regularly distributed over the blowing head and in the front wall thereof to form rows parallel with the width of the block. The slots communicate with blowing-holes of multiple width in the region of the non-laminated lower part of the front wall of the block.

A further object of the invention is to provide a composite blowing head of the above described character which is built up or made of separate laminae or segments.

Another object of the invention is to provide a blowing head which is assembled from grate-like profiled rods bedded into each other by means of adapted joints.

Among the advantages of the new form of the blowing head may be mentioned the very favorable proportion between cooling surface and furnace surface; and the high indeforability (deformation resistance) of the block. The air guidance and the cooling effect are much better than in blocks of known construction because the design of the blowing head obviates or mitigates especially heavy accumulations of solid material as well as considerable reductions of material in same locations. The material is distributed nearly evenly in

2

all places so that the expansions due to heat or the cooling is nearly uniformly distributed in the block in practically all directions.

A further advantage of the novel blocks is in that the heads of adjacent blowing blocks are situated side by side without touching each other; that means, also without cement or another binder.

One form of the novel construction is illustrated by way of example in the accompanying drawings in which Figure 1 is a perspective view of three blowing heads constructed in accordance with my invention which are situated side by side adjacent to each other.

Figure 2 is a perspective view of three segments of a single block, which segments are shown in exploded view.

Figure 3 is a perspective view of one segment.

In the underfeed furnace, the fuel (e.g. coal) is fed in known manner by a screw (not shown) which works in a pipe, the fuel passing through an enlarged part of the pipe and being fed upwardly into the retort or furnace bed which is built of blowing head resting on the side wall 3 of the enlarged part of the pipe. Collar 2 of the side wall 3 is received in grooves 1 of segments 7 of the blowing heads. These blowing heads (tuyère blocks) form, together with the corner blocks (not shown as they form no part of this invention) and the side walls 3, a right-angled retort or furnace bed. On the outside, the tuyère blocks are connected to a ring which is built of horizontal plates 5 supported by the wall of the tuyère box 6.

As may be seen in Figs. 1 and 2, every tuyère block (blowing head) consists of a main lamina or segment 7 and of filler-laminae or segments 8 which are adjacent to and placed sidewise to the main segment. The segments 7 and 8 are formed with ribs 9 which extend from both major surfaces of the web of each segment adjacent to the latter's meeting upper and front end faces which extend from both major surfaces of the web of each segment adjacent to the latter's upper and front end faces in such manner that, if the segments are assembled (see Fig. 1), the ribs 9 define air-channels 10 through which the combustion air is forced from the tuyère box 6 into the furnace bed. The term "web," as utilized in this specification and in the appended claims, is intended to denote the upright plate-like main body portions of segments 7, 8 from which the ribs 9 extend. As the air passes through the blocks, it cools selected zones of the latter which are heated to the highest temperatures during the combustion of the fuel (e.g. coal) in the furnace.

The front part of each main segment 7 is formed with two sets of substantially parallel ribs 11 which, together with similar ribs 11 of an adjacent and abutting main segment, define air openings 12 through which additional combustion-air from the tuyère box 6 is blown into the retort. Ribs 11 as well as a pair of ribs 17 which latter do not extend fully to the front end face of a main segment are disposed at both sides or major surfaces of the web of each segment 7. These relatively long ribs 11 and 17 are adjacent to the lower zone of the front end face of the upright web of each main segment, while the relatively short ribs 9 extend from the web of each segment 7 adjacent to the latter's upper end face and the upper zone of its front end face.

The rear end of each main segment 7 is formed with a collar 13 which extends the full height thereof and abuts against a similar collar of an adjacent main segment 7. Each collar 13 has an outer lug 14 which enters into a suitable recess in the adjacent plate 5. The lower end of collar 13 is provided with a rib 15 defining a shoulder which supports the rear ends of webs of filler segments 8. Each filler segment 8 has a nose portion

16 which is spaced from and above the uppermost rib 11 of the adjacent main segment 7. The nose portions of filler segments 8 fill out the space between two adjacent segments 7 above their uppermost ribs 11 between the front end faces of segments 7 and the offset ribs 17 in that said portions 16 extend downwardly over members 17. The latter are received in cutouts 18 provided in the filler segments 8. Consequently, all filler segments 8 are secured in the main planes of their webs against movements under the influence of heat or distortion.

As may be seen in Fig. 1, two filler-segments 8 are provided on each side of a main segment 7, but it is equally within the scope of my invention to provide only one segment 8 on each side of the main-segment 7 to make a complete block. On the other hand, there may be provided more than two filler-segments on each side of a main segment.

The upper parts of each main-segment 7 and of its four filler-segments 8 which together form a complete tuyère block are as much smaller as the ribs 11 on the front and the collars 13 on the rear of the segment 7 as they will expand under heat so that all segments in their working position have in heated condition the same width as the shaped parts. By this simple means it is prevented that the upper part of the segments expands under heat more than the front or rear parts.

The side or major surfaces of the webs of segments 8 are formed with ribs similar to ribs 9 on the major surfaces of the webs of main segments 7; thus, two adjacent segments 8 define therebetween openings similar to openings 10 formed between a main segment 7 and the abutting filler-segment 8. Moreover, all segments are provided with round bores 19 passing through the webs of said segments through which can be threaded a rod 20 for firmly holding together the blocks.

The ribs 9 on the webs of main segments 7 and laminae 8 could be formed only on one side or major surface thereof. The openings 10 in the head of each block, that is, the openings between the respective upper and front end faces of segments 7 and 8, also can be united into vertical slots in accordance with a modification of the invention.

The working temperatures of underfeed-stokers with tuyère blocks according to the invention are at about 200° C. and thus lower than with ordinary blowing heads. The weight of the blowing head according to the invention is about twice that of ordinary blowing heads.

After switching off the air in a furnace with known blowing heads the temperatures rise to between about 350° C. and about 530° C.

Under the same circumstances, this temperature range is between about 200° C. and 300° C. if blowing heads according to the present invention are used.

What is claimed is:

- 5 1. A composite tuyère block for the side walls of underfeed stokers which comprises, in combination: a main segment having an upright web with a pair of major surfaces, an upper and a front end face, said front end face having an upper zone and a lower zone, short transverse ribs extending from said major surfaces adjacent to the upper end face and to the upper zone of said front end face, and long transverse ribs extending from at least one major surface in the proximity of the lower zone of said front end face; at least one filler segment adjacent to each major surface from which said long ribs extend, each filler segment having an upright web with a pair of major surfaces, an upper and a front end face, a forward end and a rear end, and ribs extending transversely from its major surfaces adjacent to the upper end face and to the front end face thereof, the ribs of each filler segment abutting the short ribs of the main segment and defining air channels therebetween, the upper end face and the upper zone of the front end face of said main segment being aligned with the upper end face and the front end face, respectively, of each filler segment, and the long ribs of said main segment extending beneath and supporting the forward end of each filler segment; and means forming part of said main segment for supporting the rear end of each filler segment.
- 10 2. A tuyère block as set forth in claim 1, wherein the means for supporting the rear end of each filler segment comprises a collar extending transversely from the web of said main segment and having a shoulder extending beneath the rear end of each filler segment.
- 15 3. A tuyère block as set forth in claim 2, wherein the uppermost long ribs on which the forward end of each filler segment is supported are offset from the front end face of said main segment and each filler segment has a nose portion extending downwardly over said offset long ribs.
